UNITED STATES PATENT OFFICE.

FRED SCHLESSER, OF RIVER GROVE, ILLINOIS, ASSIGNOR TO AJAX SPRING STABILIZER COMPANY, OF CHICAGO, ILLINOIS, A CORPORATION OF ILLINOIS.

SPRING COVER.

Application filed June 3, 1926. Serial No. 113,452.

This invention relates to improvements in spring covers and more particularly to covers for springs for vehicles such as automobiles, and the general object thereof is to provide 5 a spring cover which will preserve the life of the spring which will aid in preventing breakage of the spring which will increase its efficiency and maintain it in substantially its original condition throughout its life.

10 A further object of the invention is to provide a spring cover formed of fabricated units adapted to conform to and closely to embrace a corresponding section of a spring.

15 A further object of the invention is to provide spring cover units of the character described with overlapping extensions adapted to be permanently secured together after the unit has been applied to the spring.

20 A further object of the invention is to provide spring cover units of the character described so constructed, that a plurality of units may be applied individually to the spring with their adjacent ends telescopically arranged thereby permitting relatively 25 longitudinal movement of the units during the flexion of the spring.

An important object of the invention is 30 to provide spring cover units of the character described which can be readily applied to the spring intermediate of the clips thereof without the necessity of the removal of the clips.

35 A further object of the invention is to provide spring cover units of the character described having a tongue adapted to extend beneath the spring clip and telescopically to enter the adjacent end of a spring cover unit located on the opposite side of the clip.

40 A further object of the invention is to provide a sheet metal unit of the character described having interlocking extensions adapted to be interengaged after the unit has been applied to the spring and thereupon folded to provide a lock seam permanently securing the unit in place upon the 45 spring.

An important object of the invention is 50 to provide permanently closed spring cover units of the character described which will avoid the necessity of using the usual spring clips.

55 A further object of the invention is to provide a covering for a laminated spring, comprising a lubricant containing wrapping and means closely enclosing said wrapping

operable in conjunction therewith to prevent separation of the laminations of the spring and maintain such laminations in constant frictional engagement thereby acting as a shock absorber especially to retard the rebound of the spring.

More particularly, the invention contemplates the provision of a lubricant containing wrapping for a spring enclosed in closely fitting units formed of sheet metal having the extensions adapted to be interlocked after the units have been applied to the spring, thereby providing a casing which will retain the laminations of the spring in constant frictional engagement for the purpose above stated.

Preferred embodiments of the invention are illustrated in the accompanied drawings in which:—

Fig. 1 is a side elevation of a semi-elliptic 75 spring having the present invention applied thereto.

Fig. 2 is a perspective view of an end portion of a spring illustrating preferred spring cover units embodying the invention applied thereto and broken away to show the tongue of one unit extending beneath one of the usual spring clips and telescopically entering an adjacent unit.

Fig. 3 is a view of an inverted end portion 85 of the spring illustrating the manner in which the units provided with interlocking extensions are applied thereto, and showing also longitudinally extending insert strips reinforcing the seamed face of the unit or units.

Fig. 4 is a perspective view of a preferred form of unit provided with a tongue adapted to extend beneath the spring clip, but which may be omitted when the ends of adjacent units are telescopically arranged.

Fig. 5 is a perspective view of an insert strip.

Fig. 6 is a perspective view of a spring, partly in section, and partly broken away 100 having a lubricant containing wrapping enclosed in a sheet metal cover unit, the free edges of which are permanently connected by a lock seam.

Fig. 7 is a perspective view of a portion 105 of a semi-elliptic spring showing the present invention applied thereto, and the overlapping extensions of respective units permanently connected together by spot welding.

Fig. 8 is a view of a usual type of canti-

lever spring mounted upon a section of a vehicle frame and provided with a spring cover embodying the invention.

Fig. 9 is a detail view of an end portion 5 of a spring illustrating a lubricant containing covering spirally wrapped thereupon.

Fig. 10 is a similar view illustrating a lubricant containing wrapping in sheet form.

Fig. 11 is a sectional view through the 10 spring, the wrapping and sheet metal spring cover illustrated on the line 11-11 of Fig. 8.

The spring 1 illustrated in Figs. 1, 2 and 3 of the drawings, comprises a long leaf 2 having at its ends the usual eyes 3 and 4 and 15 a series of underlying progressively shorter leaves 5 which are joined together at their central portion by U-bolts 6 which clamp the same together and to the spring saddle 7 which ordinarily is connected or forms a 20 part of the axle of the vehicle. Thus a laminated spring construction is provided in which the leaves normally engage one another throughout their entire length and move longitudinally relatively to each other 25 and to the spring.

As illustrated in Figs. 1, 2 and 3, spring clips 8 and 9 embrace the leaves of the spring at suitable distances from the U-bolts 6 and from each other to hold the leaves in alignment and to prevent undue separation of the 30 leaves or laminations during the rebounding movement of the spring. Such spring covers as have been heretofore employed to enclose closely the leaves of the spring, have 35 required the removal of the spring clips to permit their application to the spring.

The present invention contemplates a provision of spring covering devices which avoid the necessity of thus removing the 40 usual clips, although the spring cover forming the subject matter of this invention is made of such material and so constructed as to avoid the necessity of using such usual spring clips. When thus employed without 45 spring clips, the spring cover performs also the function of the spring clips.

In the application of the present invention, the spring desirably is provided with a lubricant containing wrapping which is 50 closely enclosed by a series of fabricated units preferably of sheet metal which are provided with overlapping portions adapted to be permanently connected together after the units have been applied to the respective 55 spring sections to which they conform.

In the particular construction illustrated in Figs. 1-7 inclusive, a series of similar springs cover units are employed, these units being made of different sizes to conform to 60 the different portions or sections of the spring to which they are to be applied.

One of these units is illustrated in Fig. 4 in an inverted position and comprises a plate of sheet metal which is fabricated to 65 present a flat top 10 adapted to rest upon

the top of the long leaf of the spring with side members 11 and 12 to engage respectively the sides of a spring section. These side portions are bent at right angles to form bottom sections 13 and 14 adapted to 70 engage closely upon the under faces of superimposed lower leaves. The bottom section 13 is provided with an extension 15 which extends substantially at right angles to the plane of the section 13. The section 75 14 is likewise provided with an extension 16 which is bent at substantially right angles to the plane of the section 14. The extension 16 is again bent substantially at right angles to form flange 17 which is adapted to 80 be folded over the extension 15 of the section 13 thus producing an interengagement between the extensions of the respective bottom sections of 13 and 14. These interengaging extensions can then be folded down 85 to form a locked seam 18 as illustrated in Fig. 3 which preferably extends longitudinally of the under face of the spring.

The top portion 10 of the spring cover unit illustrated in Fig. 4 is provided with a 90 tongue 19 extending from one end of said top portion and adapted to pass beneath the spring clip and telescopically to engage a similar unit which is on the opposite side of the spring clip, but such tongues are not required when the adjacent ends of successive units are telescopically arranged; furthermore, such tongues are not necessarily employed.

The spring cover illustrated in Fig. 1 100 comprises a unit 20 which is interposed between the spring clip 8 and the saddle 7 and desirably may be provided with a tongue 19 which extends beneath the clip 8. Two cover units 21 and 22 of similar construction but 105 fabricated to conform to the respective portions of the spring sections are employed between the spring clip 8 and the spring clip 9, while the remaining end portion of the spring is provided with a single unit cover 110 23. These units are tapered to conform substantially to the shape of sections of the spring which they enclose and the smaller end of the cover unit 21 extends telescopically into the larger end of the cover unit 22. 115 The cover unit 22 is desirably provided with a tongue 19 which extends telescopically into the larger end of the unit 23 which encloses the end portion of the spring.

In the application of the spring cover to 120 the spring, a suitable lubricant is applied to the leaves of the spring and the spring section enclosed in a wrapping of fibrous or other suitable material, preferably a heavy duck. The sections 13 and 14 of each of the fabricated cover sections, illustrated in Fig. 4, are then spread apart sufficiently to enable the unit to be applied to the section of the spring to which it conforms and after having 125 been applied, the extensions 15 and 130

16-17 of the sections 13 and 14 are caused to interengage, by the use of pliers or other suitable tools. These interengaged extensions are then folded down upon the spring 5 and pressed or hammered tightly together to produce a permanent locked joint. Thus each section of the spring which is defined by the respective clips is adapted to be separately wrapped and covered without the necessity of removing the spring clips.

While any suitable lubricant may be employed, the present invention contemplates the employment of a viscous lubricant having water-repelling properties and containing 15 a rust-preventing composition. By the use of such a viscous composition, considerable adhesion is produced between the adjacent faces of the spring leaves, and the composition also serves to cause the wrapper to 20 adhere to the spring leaves and overlapping portions of the wrapper to adhere to each other.

The lubricant containing wrapping which closely embraces the spring and the inelastic 25 or inexpandible metallic covering, cooperate to maintain the leaves or laminations of the spring in constant frictional engagement throughout their lengths and effectively preventing separation of the leaves thereby producing 30 a shock absorbing action.

The covering units, however, permit the relatively longitudinal movement of the spring leaves or laminations which results from the flexing of the spring without any 35 restriction thereof.

An additional insert beneath the seam which joins the overlapping sections of the bottom portion of the units, may if desired, be employed. Such an insert is shown in 40 Fig. 5 as comprising a sheet metal plate 24. This insert is placed beneath the seam of one or more of the units before the seam is interlocked, and after the seam is interlocked, the extending end portions 25 and 26 thereof are 45 folded over and upon the outer face of the seam and pressed or hammered tightly down. The insert may be of any desirable length either to extend beneath a single unit such as the end unit 23, or adjacent units 50 such as the units 21 and 22 illustrated in Fig. 3.

In Fig. 6 a section of the spring, its wrapping and cover together with the insert plate is illustrated. The lubricant 27 being applied 55 to the spring leaves, and enclosed in a wrapping 28 of duck or other suitable material which is in turn, enclosed by the sheet metal unit. The extensions 16 and 17 of the unit are interlocked and the insert 24 is located 60 between the seam connecting the lower section of the unit and the wrapping 28.

While the invention has been above described as applied to springs provided with 65 spring clips, it will be obvious that the spring clips may be omitted while closed

cover units of the character described herein are employed. It will also be obvious that such cover units may be used not only with elliptical types of springs but in the cantilever and other types of spring. It will also be 70 obvious that other means than the lock seam may be employed to secure the overlapping extensions of the units.

In Fig. 7 the invention is illustrated as applied to a spring which is not provided 75 with spring clips. In this construction three spring cover units 29, 30 and 31 are employed. These units are of general rectangular form to conform to the respective sections of the spring which they embrace 80 and are provided with flat overlapping extensions 32 and 33, the outer of which, 33, desirably extends the full width of the spring and is secured to the underlying section 32 by spot welds 34 located at suitable distance 85 from one another. These units are not provided with tongues but the narrow ends of each unit telescopes into the larger end of the adjacent unit.

In Fig. 8 a full cantilever spring which is 90 employed in certain types of cars, is illustrated.

In this construction, the wrapper for the spring may be formed of a spirally wound band 35 of suitable fabric, such as heavy 95 duck, or the wrapping may be in the form of a sheet 36 cut in such a manner as to be wrapped tightly around the spring and present overlapping portions 37 and 38 which desirably may be overlapped the full width 100 of the spring either on the top or the bottom. The overlapped extensions of the units desirably are located beneath the bottom of the spring, as is shown in Figs. 3 and 7, in which the spring is illustrated in inverted 105 position, such overlapping extensions may however be located on the top or either side of the spring, but preferably on the bottom or the inside where they will not be visible.

By thus forming the spring cover in units 110 fabricated to conform to different sections of the spring, a construction is provided in which the units may be applied to usual types of springs which are provided with spring clips, or if employed for factory 115 equipment or upon springs from which clips have been removed, the units may be assembled upon the spring in such overlapping relation as not only to provide a lubricant containing cover for the spring, but also to take 120 the place and perform the function of the usual spring clips.

While the invention has been described with particular reference to the use of sheet metal units, it will be obvious that other substantially inelastic materials may be employed in the form of units, within the spirit and scope of the present invention.

The present invention contemplates the use of any suitable material to enclose the 130

lubricant containing wrapping in such a secure manner, as to maintain the laminations or leaves of the spring in constant frictional engagement, and to prevent separation of the leaves or laminations particularly during the rebounding movement of the springs. The covering units, desirably, are of such character as to permit the wrapping to move freely relatively thereto, but the wrapping is adapted so to embrace the spring as to exert a restraining action upon relative longitudinal movement of the leaves, particularly where the spring is extremely flexed.

15 It will be understood, that the particular embodiments of the invention disclosed herein are of an illustrative character and are not restrictive of the meaning and scope of the claims.

20 Having thus described the invention, what is claimed as new, and desired to be secured by Letters Patent, is:

25 1. In a spring cover, a plurality of sleeve-like units adapted for application to the spring, each of said units having a split base the free edges of which are adapted to be wrapped together to secure the unit to the spring, a tongue integral with the top portion of certain units for releasable engagement with the contiguous unit, and an insert adapted for disposal longitudinally of said base within the series of sleeve like units, the ends of said insert extending beyond said base and adapted to be bent back upon the 30 wrapped ends of that member.

35 2. In a spring cover, a plurality of units adapted for application to the spring, two of said units having their meeting ends telescoped into each other, an insert within said 40 units extending longitudinally of said two units and its ends folded back upon the remote ends of said two units, and the tongues formed upon certain units for engagement with a contiguous unit.

45 3. A spring cover, comprising a plurality of independent units fabricated to conform to and closely to embrace corresponding sections of the spring, and having edges adapted for interlocking engagement around said 50 spring.

55 4. A spring cover, comprising a plurality of independent units fabricated to conform to and closely to embrace corresponding sections of the spring and having edges adapted for interlocking engagement around said spring, certain of said units having telescopic adjacent ends.

60 5. A spring cover for a laminated spring having spring clips, comprising substantially inelastic units fabricated to conform to and closely to enclose the respective sections of the spring defined by the spring clips, and having edges adapted for interlocking engagement around said spring, including a 65 plurality of units independently movable

relatively to each other and longitudinally of the spring having telescoping adjacent ends intermediate of clips defining relatively long spring sections.

6. A spring cover, comprising a plurality of metallic units fabricated to conform to and closely to enclose corresponding sections of the spring, each unit having overlapping portions adapted to be permanently interlocked after the unit is applied to the spring.

7. A spring cover, comprising a plurality of tapering metallic units fabricated to conform to and closely to enclose corresponding sections of the spring and telescopically to engage, each unit having overlapping portions adapted to be permanently interlocked when the unit is applied to the spring.

8. A spring cover, comprising a plurality of tapering units fabricated of sheet metal to conform to and closely to enclose corresponding sections of the spring, each of said units having overlapping edge portions forming interlocking members adapted to be interengaged after the unit is applied to the spring and thereupon forced into permanent locking position and the adjacent ends of said units and also the adjacent ends of the interlocking members forming the seam being telescopically arranged.

9. A spring cover unit fabricated from sheet metal to conform to and closely to embrace the corresponding section of a spring and having overlapping members adapted to be permanently locked together after the unit is applied to the spring.

10. A spring cover unit fabricated from sheet metal to conform to and closely to enclose a corresponding section of a spring, and having overlapping edge flanges forming interlocking members adapted to be interengaged after the unit is applied to the spring and compressed to form a permanent lock seam.

11. A covering for a laminated spring, comprising a lubricant containing wrapping closely enclosing said spring and substantial inelastic means closely enclosing said spring wrapping and an interlocking joint for said inelastic means acting to maintain the relation of said means and said wrapping whereby to retain the laminations of said spring in constant frictional engagement.

12. A covering for a laminated spring, comprising a lubricant containing wrapping closely enclosing said spring and a metallic covering closely enclosing said spring wrapping and an interlocking joint for said inelastic means acting to maintain the relation of said means and said wrapping whereby to retain the laminations of said spring in constant frictional engagement.

13. A covering for a laminated spring, comprising a wrapping closely enclosing said spring and containing a viscous water-repellant and rust-preventing composition

- and a cover of substantially inelastic material closely enclosing said spring wrapping and an interlocking joint for said inelastic means acting to maintain the relation of 5 said means and said wrapping whereby to retain the laminations of said spring in constant frictional engagement.
14. A covering for a laminated spring, comprising a lubricant-containing wrapping 10 of fibrous material closely enclosing said spring and a cover formed of independent sheet metal units fabricated to conform to and closely to embrace and enclose corresponding wrapped sections of the spring, 15 and having edges adapted for interlocking engagement around said spring.
15. The combination with a laminated spring of spring clips and a covering for 20 said spring, comprising wrapping of fabric closely enclosing the sections of the spring defined by the spring clips and containing a lubricant and a cover formed of independent sheet metal units fabricated to conform to and closely to embrace and enclose said 25 spring sections and wrapping, the units on opposite sides of a spring clip having their adjacent ends abutting the clip.
16. A covering for a laminated spring 30 having spring clips comprising wrapping of fabric embracing the sections of the spring defined by the spring clips and containing a lubricant and a cover formed of independent sheet metal units fabricated to conform to and closely to embrace said spring sections 35 and wrapping and having overlapping longitudinal edges adapted to be permanently locked together after said metallic units have been assembled upon the spring.
17. A covering for a laminated spring 40 comprising a lubricant-containing wrapping closely embracing and enclosing said spring, operable to prevent separation of the laminations of the spring and partially to restrain relative longitudinal movement of 45 said laminations during extensive flexions of the spring and a cover of inelastic material closely enclosing said wrapping but movable relatively thereto during the flexions of the spring, said cover having edges adapted for 50 interlocking engagement around said spring.
18. A covering for a laminated spring 55 having spring clips, comprising a sectional lubricant-containing wrapping closely embracing and enclosing the respective sections of the spring defined by the spring clips, operable to prevent separation of the laminations of the spring and partially to restrain relative longitudinal movement of said laminations during extensive flexions of the 60 spring, and a cover composed of sheet metal units fabricated to conform to the respective sections of the spring and independently applicable thereto closely enclosing said wrapping but movable relatively thereto during
- the flexions of the spring, said cover having 65 edges adapted for interlocking engagement around said spring.
19. The combination of a laminated spring, spring clips, a cover for said spring, 70 comprising substantially inelastic units fabricated to conform to and closely to enclose the respective sections of the spring defined by the spring clips, the units on opposite sides of a spring clip having their adjacent ends abutting the clip.
20. The combination of a laminated spring, clips therefor, and a cover therefor, 75 comprising substantially inelastic units fabricated to conform to and closely to enclose the respective sections of the spring defined by the spring clips, the units on opposite sides of a spring clip having their adjacent ends abutting the clip, one of said units having a tongue extending from the abutting end through the spring clip and telescopically 80 engaging the unit which abuts the opposite side of the clip.
21. A spring cover, comprising a plurality 85 of independent units fabricated to conform to and closely to embrace corresponding sections of the spring, and means whereby the edges of said units may be drawn into interlocking engagement.
22. A spring cover, comprising a plurality 90 of independent units fabricated to conform to and closely to embrace corresponding sections of the spring, certain of said units having telescoping adjacent ends, and means whereby the edges of said units may be 95 drawn into interlocking engagement.
23. A cover for a laminated spring, comprising a lubricant-containing wrapping of fibrous material closely enclosing said spring, and a cover formed of independent sheet metal units fabricated to conform to 100 and closely to embrace and enclose corresponding wrapped sections of the springs, and means whereby the edges of said units may be drawn into interlocking engagement.
24. In a spring cover, a plurality of sleeve-like units adapted for application to the spring to completely encompass the same and each comprising a single piece of material, each of said units having a longitudinally split base the free ends of which 105 are adapted to be wrapped together to secure the unit to the spring, a tongue integral with the top portion of certain units for releasable engagement with the contiguous unit, and an insert adapted for disposal longitudinally of said base, the ends of said insert extending beyond said base and being adapted to be bent back upon the wrapped 110 ends of that member.
- In testimony whereof, I have signed my 115 name to this specification.

FRED SCHLESSER.
